WATER SPRINKLER

Orton H. Englehart, Glendora, Calif.

Application December 18, 1933, Serial No. 702,902

10 Claims. (Cl. 299—69)

My invention relates to a water sprinkler of the slow rotary type and particularly designed for use in orchards, gardens, golf courses, lawns and the like and the principal object of my invention is, to provide a relatively simple, practical and inexpensive sprinkler wherein the jet nozzle or nozzles are caused to slowly revolve by small increments or step by step movements so as to effectively distribute water throughout a considerable area immediately surrounding the sprinkler.

Further objects of my invention are, to generally improve upon and simplify the construction of the existing forms of slow rotation sprinklers, further, to provide a sprinkler of the character referred to having relatively few operating parts and further, to provide a sprinkler whereby the rotary arm that carries the jet nozzle or nozzles is caused to rotate with a step by step movement as a result of repeated impacts that are delivered by a spring held member and the operation of which latter is brought about by a jet of water that issues from one of the said distributing nozzles.

With the foregoing and other objects in view my invention consists in certain novel features of construction and arrangement of parts that will be hereinafter more fully described and claimed and illustrated in the accompanying drawing in which:

Fig. 1 is a top view of a sprinkler constructed in accordance with my invention.

Fig. 2 is a side elevational view of the sprinkler with parts thereof in vertical section.

Fig. 3 is an enlarged detail section taken on the line 3—3 of Fig. 2.

Fig. 4 is a cross section taken on the line 4—4 of Fig. 3.

Referring by numerals to the accompanying drawing which illustrates a preferred embodiment of my invention, 10 designates a short vertically disposed tubular member that is suitably connected, preferably by means of a coupling 11 to a pipe 12 that serves as a duct for water under pressure and mounted for rotation within said member 10, is a tube 13 that is provided on its lower end with a flange 14.

Interposed between flange 14 and the lower end of tubular member 10, is a suitable gasket or packing ring 15.

Detachably secured to the upper end of tube 13, that projects through tubular member 10, is the lower end of a Y connection 16, the passage-ways through which are stream lined in order

to permit the free passage of water through said connection.

Secured to one of the arms of the Y connection, is a tubular arm 17 that preferably occupies an inclined position with respect to vertical and horizontal planes and carried by the outer end of this arm, is a conventional jet nozzle 18.

Secured to the other arm of the Y connection 16, is an inclined tubular arm 19, the outer end of which carries a jet nozzle 20.

Formed integral with and projecting outwardly from one side of nozzle 20, is a short plate 21 and seated therein, is a pin or screw 22, having a conical point 23 that occupies a position in the path of travel of the jet of water that issues from nozzle 20. This pin or screw is for the purpose of breaking up the jet of water that issues from nozzle 20 and causing a portion of said water to be distributed over the ground adjacent to the sprinkler and within that area that is encompassed by the area upon which water from the main nozzle 18 is distributed.

Pin 22 may be rigidly fixed to plate 21 or it may be in the form of a screw as illustrated so as to adjust the position of the pointed end relative to the jet of water that issues from the adjacent nozzle.

Under some conditions it may be desirable to arrange a pin such as 22 in nozzle 18 rather than in nozzle 20 or if desired, such pins may be located in both nozzles.

Seated in the center of the Y connection 16, is the lower end of an upwardly projecting post 24 and mounted to rotate freely thereupon, is a sleeve 25.

The upper end of the sleeve is seated in the depending leg of a T connection 26 and the upper end of post 24 is provided with a conical bearing 27 that engages the upper part of the wall of the connection 26.

A torsional spring 28 surrounds sleeve 25 and is arranged between the connections 16 and 26 with the upper end of said spring looped over connection 26 and the lower end of said spring looped around one of the arms of connection 16.

The inner end of a horizontally disposed rod 29 is seated in one of the horizontal arms of connection 26 and secured to the outer end of this arm and occupying an inclined position corresponding with the inclined position of tubular arm 19 and jet nozzle 20, is an open ended box-like member 30.

Under normal conditions or while the sprinkler is not in use, the rear wall of member 30 rests against the outer portion of plate 21, being held

in such position by the tension exerted by spring 28 and thus said member 30 is positioned directly in advance of the jet opening of nozzle 20.

The outer portion 31 of the rear wall of housing 30 is inclined forwardly so as to occupy a position directly in line with the jet opening through nozzle 20, thereby providing an inclined vane or surface that is impinged by the jet of water issuing from said nozzle.

10 The front wall of the housing 30 is extended a substantial distance beyond the end of the inclined wall or vane 31 as designated by 32 and the outer portion of this extended wall is curved rearwardly, or away from vane 31, thus forming 15 a deflector to cause the water that discharges through member 30 to discharge outwardly at an angle relative to the vertical plane occupied by the sprinkler arms 17 and 19.

Seated in the fitting 26, opposite from and in 20 line with arm 29, is a short arm 33, the outer end of which carries a weight 34, that functions as a counter balance for the weight of arm 29 and parts carried thereby.

In the operation of my improved sprinkler 25 water under pressure from supply pipe 12 flows upwardly through tube 13, thence through Y connection 16 and thence through tubular arms 17 and 19 and such water discharges in jet form through the jet nozzles 18 and 20.

30 The greater portion of the jet of water issuing from nozzle 20, strikes against vane 31 and is deflected thereby against the extended plate 32 and the reaction of water leaving the latter causes the housing 30 and arm 29 to swing in an 35 arc away from jet nozzle 20 and arm 19, the length of which arc depends upon the resistance offered by torsional spring 28, also the total weight of the swinging assembly and the force of the water issuing from the jet nozzle.

40 The reactive action just described causes the oscillating member to swing rather than to cause the entire sprinkler to rotate backward because the resistance of spring 28 is less than the resistance offered by the friction caused by the upward thrust of flange 14 and gasket 15 against 45 tubular member 10, which thrust is due to the pressure of the water passing through pipe 12 and tube 13.

As soon as the inertia of the swinging parts is 50 expended, the torsional spring rotates the swinging assembly in the opposite direction, during which movement the swinging assembly turns on the axis at the upper end of post 24 and toward the end of said swinging movement the member 30 is traveling with such velocity that it 55 cuts through the jet from nozzle 20 and finally strikes against the extended plate 21, thereby causing the entire sprinkler to rotate upon the fixed tubular member 10 for a relatively small portion of its complete rotation.

60 This operation repeated continuously effects the complete rotation of the sprinkler with a step by step movement and thus water from the two nozzles is distributed throughout a considerable area immediately adjacent to the sprinkler.

65 The partial vacuum produced on the outside of vane 31 and the rear wall of member 30 as the latter cuts into the jet of water, tends to pull said member 30 further into said jet and such action aids materially in producing a steady, strong oscillation.

It is desirable that the oscillating arm of the 75 sprinkler and also the rotating part thereof be balanced with respect to their respective axes so that the sprinkler will function properly even

though the plane of rotation is not horizontal. Under some conditions it may be desirable to permit water to issue from nozzle 20 only, in which event the tubular arm 17 and nozzle 18 may be replaced by a suitable counter weight.

Thus it will be seen that I have provided a slow rotation water sprinkler that is relatively simple in construction, inexpensive of manufacture and very effective in performing the functions for which it is intended.

10 It will be understood that minor changes in the size, form and construction of the various parts of my improved water sprinkler may be made and substituted for those herein shown and described without departing from the spirit of my invention, 15 the scope of which is set forth in the appended claims.

I claim as my invention:

1. In a water sprinkler, a tubular arm mounted for rotation on a substantially vertical axis and 20 provided with a jet opening, an arm mounted for oscillatory movement upon said tubular arm and having an axis that is substantially coaxial with the axis of said tubular arm and arranged to impact said first mentioned tubular arm at a set 25 point in its oscillation and means carried by said oscillating arm for causing said tubular arm to rotate with step by step movement as a result of impacts of the oscillating arm against said tubular arm.

2. In a water sprinkler, a tubular arm mounted for rotation and provided with a jet opening, an arm mounted for oscillatory movement upon said tubular arm, the axes of said oscillating arm and tubular arm being substantially the same and 35 means whereby said oscillatory arm is caused to oscillate and strike against said rotary tubular arm to effect step by step rotation of the latter.

3. In a water sprinkler, a rotatably mounted tubular member provided with a jet opening, an arm mounted for oscillatory movement on said tubular member, a vane carried by said arm, said oscillating arm arranged to impact said tubular member at a certain point in its oscillation, said vane being arranged to enter the jet of water issuing from the jet opening in the tubular arm and to move the oscillating arm away from the tubular arm, and a spring arranged between said oscillatory arm and said rotatably mounted arm for causing said oscillatory arm to strike against 40 said tubular arm and impart step by step rotary movement thereto.

4. In a water sprinkler, a rotatably mounted tubular member provided with a jet opening, an arm mounted for oscillatory movement on said tubular member and arranged to impact said tubular member at a certain point in its oscillation, a vane carried by said oscillatory arm and normally positioned in the path of travel of the jet of water issuing from the jet opening in said tubular arm which vane is arranged so as to be moved away from the tubular member as a result of the impact of the jet of water issuing from said jet nozzle and a spring arranged between said arm and tubular member for yieldingly resisting the movement of said arm as the vane thereon is impinged by the jet of water issuing from the jet opening in said tubular member and for causing said arm to periodically strike against said tubular member and impart step by step rotary movement thereto.

5. In a water sprinkler, a rotatably mounted tubular member provided with a jet opening, an arm mounted for oscillatory movement on said tubular member, a vane carried by said oscillatory

- arm and normally positioned in the path of travel of the jet of water issuing from the jet opening in said tubular arm which vane occupies an angular position with respect to the direction of flow of the jet of water issuing from the jet opening so as to be moved away from the tubular member by the force of the jet issuing from said jet opening and a spring arranged between said oscillatory arm and said tubular member for yieldingly resisting the movement of said arm away from said tubular member as a result of the reaction of the deflected jet of water issuing from said jet opening against said vane and for swinging said arm toward said tubular member and striking the same with sufficient force to impart step by step rotary movement to said tubular member.
6. In a water sprinkler, a rotatably mounted tubular member provided with a jet opening, an arm mounted for oscillatory movement on a vertical axis on said tubular member, a housing provided with a vane carried by said oscillatory arm, said vane having an inclined portion that is normally positioned in the path of travel of the jet of water issuing from the jet opening in said tubular member and so constructed and arranged as to swing the end of the oscillatory arm away from the tubular member as a result of the force of the jet of water issuing from said jet nozzle against said vane, the housing arranged to cut through the jet and strike against a portion of the tubular member at one end of the oscillatory movement of said arm, and a deflector carried by said housing oppositely arranged with respect to said vane, and a spring arranged between said tubular member and oscillating arm for yieldingly resisting the swinging movement of said oscillating arm away from said tubular member.
7. In a water sprinkler, a rotatably mounted tubular member provided with a jet opening, an arm mounted for oscillatory movement on said tubular member, a vane carried by said oscillatory arm and normally positioned in the path of travel of the jet of water issuing from the jet opening in said tubular member and a pin carried by said tubular member and projecting into the path of travel of the jet of water issuing from said jet opening.
8. In a water sprinkler, a pair of oppositely arranged rotatably mounted tubular members, each provided with a jet opening, an arm mounted for oscillatory movement on a vertical axis upon said tubular members and arranged to impact one of said tubular members at a certain point in its oscillation, a vane carried by said oscillatory arm having an inclined portion that is normally positioned in the path of travel of the jet of water issuing from the jet opening in one of said tubular members, and so arranged that it moves the oscillating arm away from the tubular arm.
9. In a water sprinkler, the combination with a rotatably mounted tubular member having a jet opening and an arm mounted for oscillatory movement on said tubular member, said tubular member and arm having substantially the same axis of movement and cooperating means between said tubular member and arm for imparting oscillatory movement to said arm and causing the same to strike against said rotatably mounted member to impart step by step rotary movement thereto.
10. In a water sprinkler, a jet nozzle member mounted for rotary movement, an oscillatory member mounted on said jet nozzle member and arranged to impact said jet nozzle member at a certain point in its oscillation, a vane carried by said oscillating member and arranged to enter the jet of water and to swing the end of the oscillating member away from the jet nozzle member, a portion of which oscillatory member is inclined and adapted to enter the jet of water issuing from said nozzle for deflecting said jet, means for yieldingly resisting the oscillatory movement of said member away from said jet nozzle and tending to return said oscillatory member to said jet nozzle, and the friction in the bearing for the rotatably mounted jet nozzle being sufficient to prevent said nozzle from rotating backward under the reactionary force of the deflected jet.

ORTON H. ENGLEHART. 45
